1,973,749

SHEET FEEDING APPARATUS

Joseph Conn Dawson, London, England, assignor,
by mesne assignments, to The Cleveland Fold-
ing Machine Company, Mentor Township,
Ohio, a corporation of Ohio

Application March 21, 1930, Serial No. 437,774
In Great Britain April 6, 1929

14 Claims. (Cl. 271—52)

This invention relates to sheet feeding apparatus comprising a feed table having feeding elements tending to move sheets forwardly on a straight line, preferably one in which the feed surface is composed of a series of driven rollers arranged in parallelism thereon; and a side guide by contact with which the sheets so fed are correctly registered in their travel. Such sheet feed tables are used with particular advantage 10 in connection with folding machines, printing presses and the like. In such tables as previously constructed, the side guide referred to is arranged parallel to one of the longitudinal sides of the table and the feed rolls of the table are 15 set at an angle thereto or in oblique arrangement on the table so as to cause the sheets traveling thereover to move to the side fitted with the side guide. Where tapes are used instead of rollers, the tapes are arranged obliquely for a 20 similar purpose. With this arrangement, therefore, the side guide can only be placed at one side of the table and the lateral movement is relatively limited.

One object of this invention is to provide a 25 feed arrangement doing away with the limitations of the feed table above referred to by the provision of a side guide which can be readily adjusted for operation at any point across the feed table, and is reversible, thus enabling the 30 sheets to be registered along either side of the feed table.

Another object of the invention is to provide 35 means for imparting sidewise impetus to the sheets in order to insure their registry with the side guide where the feeding means beneath the sheets works in a direction parallel with the side guide, as through feed rolls arranged at right angles to the side guide or tapes arranged parallel therewith.

40 For the use of a reversible side guide according to this invention the rollers constituting the feed surface of the table are not arranged obliquely, but are set at right angles to the feed direction of the table and in the case of tapes, they are set parallel to the feed direction, and the side 45 guide is constituted by a bar lying at right angles to the rollers or parallel to the tapes and provided with a horizontal flange on either side thereof. At each end this bar is provided with a bracket fitted to slide on a transverse bar secured at each end of the table so as to enable this side guide to be moved across the table and secured in position at any point between its sides or at one side or the other. In order to cause the 50 sheets to be drawn towards this side guide an

additional inside or sheet deflecting bar is provided at some distance along the said side guide. This additional bar is preferably likewise adapted to slide on the cross members supporting the side guide or is otherwise associated with the latter. At a number of selected points this inclined bar is provided with runners, preferably rollers of rubber, which are arranged obliquely to the side guide and extend down from the foot of the bar into contact with the feed rolls or 65 with a tape of the table opposite the points referred to. Each of these runners is with advantage rotatably and yieldingly journalled in the forked foot of a clamp shaped to embrace the bar and adapted to be clamped thereto by 70 a binding screw or the like. These runners and their holders therefore, of which there may be any desired number, can be slid along and secured at any chosen point of the bar in contact with any desired roller of the table where roller 75 feed is used, and the point of contact on such rollers may likewise be readily varied. An arrangement of the kind described will enable either side of the feed table to be used for registering by applying the side guide and then 80 fitting the runner bar thereto in the requisite manner.

The additional bar above referred to may of course be associated with any known side guide or form part thereof. On feed tables in which the feed rolls are as hitherto arranged in an oblique manner, the runners above referred to may be replaced by balls which may be of steel or any other chosen material in order to enable the feed of the sheets to be influenced in the manner referred to for instance in the specification of patent to Hitchcock 1,680,044. When balls are employed the runner bar forms part of the side guide which is provided with holes, preferably elongated, through which the balls can pass into contact with the feed rolls, and the clamps above referred to have holes in which the balls are held and are pivotally and movably fitted so as to enable the points of contact between the balls and the rollers to be adjusted by adjusting the ball holders as may be required and securing them in the desired position.

45 Embodiments of the invention are illustrated by way of example in the accompanying drawings in which:

Figure 1 shows in side elevation a feed table 50 supplying a paper folding machine of a well known type and fitted with a reversible side guide arrangement according to one form of this invention.

105

110

- Fig. 2 is a plan view of the same.
- Figs. 3 and 4 are detail elevational views of the 80
slidable outside bar or side guide proper, partly
in section.
- 5 Figs. 5 and 6 are right angle detail elevational
views showing the runners in the form of rollers
fitted to the ends of the adjustable inside or sheet
deflecting bar.
- 10 Figs. 7 and 8 are similar views of the adjustable
runners mounted on said inside bar between
its ends.
- 15 Fig. 9 is a plan of a form of side guide com-
bined with a modified form of adjustable runner
or ball holders.
- 20 Fig. 10 is a part sectional elevation taken on
line X—X of Fig. 9.
- 25 Fig. 11 is a sectional view on an enlarged scale
taken substantially on line XI—XI of Fig. 9.
- 30 Fig. 12 shows in perspective view another form
of an adjustable ball guide for attachment to an
existing side lay.
- 35 Fig. 13 is an enlarged sectional view taken on
line XIII—XIII of Fig. 12.
- 40 Fig. 14 shows in perspective an adjustable side
lay fitted with a modified form of sheet influenc-
ing members or ball smoother guides.
- 45 Fig. 15 shows in enlarged section a detail of the
ball smoother fitting.
- 50 Fig. 16 is a fragmental plan view illustrating
another embodiment of my invention as applied
to a feed table in which the sheet moving elements
are tapes arranged parallel with the side guide,
the table being arranged to feed sheets with their
guide edges to the right.
- 55 Fig. 17 is a corresponding view of the other side
of the same table arranged to feed sheets with
their guide edges to the left.
- 60 Fig. 18 is a vertical sectional view on a larger
scale, the section being taken substantially on
the line XVIII—XVIII of Fig. 17, and
- 65 Fig. 19 is a horizontal sectional detail view
taken on the line XVIII—XVIII of Fig. 18.
- 70 Referring to Figs. 1 and 2 it will be seen that
the feed table 10 comprises feed rollers 12, which
may be driven by any suitable means, as for in-
stance by an endless belt 90 running over end
shafts 91 and 92 and over idler pulleys or shafts
93 so positioned as to insure a considerable area
of frictional contact of the belt against the pe-
ripheries of the rolls 12. The shaft 91 may carry
at one extremity a gear 94 to which driving force
is transmitted by any suitable gear train from a
motor (not shown). The feed rolls 12 are ar-
ranged at right angles to the side frames 14 and
that two rails 11 of square or rectangular section
extend across the feed table 10 parallel to the
feed rolls 12 and are rigidly held above the table
10 by short pillars 13 seated upon the side frames
14 of the feed table 10. Positioned at right angles
to the rolls 12 and extending along the whole of
the feed table on one side thereof is a bar 15
of flat rectangular section (Figs. 4 and 8) scal-
loped out to clear the rolls 12 and adjustably
mounted at either end upon the rails 11 by means
of brackets 16 (Figs. 1, 2, 3 and 4). The upper
part of each bracket 16 has jaws 17 shaped to
slidably fit on the rail 11 a milled headed clamp-
ing screw 17' being passed through the center of
the upper jaw to clamp the bar 15 in its re-
quired position. The bracket 16 has downwardly
extending members 18 slotted to receive the bar
15 and preferably riveted through to rigidly hold
the same. Attached to the bar 15 on either side
by rivets or other means are right angle members
19 forming a double flange along the length of
- 75 the bar 15 and constituting retainers on the side
guide or lay.
- An inner or sheet deflecting bar 20 of square
or rectangular section is also slidably mounted
at each end upon the rails 11 by means of
brackets 21 (Figs. 1, 2, 5 and 6). The upper por-
tion of each bracket 21 consists of wide upper
and lower jaws 22 bolted or riveted to either end
of the rail 20 on one side and embracing the rail
11 on the other side, being clamped thereto by
a milled headed screw 23. The downwardly ex-
tending portion 24 of each collar 21 is bifurcated
to receive a steel or rubber roller 25 which is
journalled in bearings mounted in slots 24' and
contacts with one of the end rollers 12 on the feed
table 10. Adjustably mounted upon the rail 20
between its ends are a number of clamps 26 (Figs.
7 and 8) each consisting of a member 26' having
jaws 27 adapted to embrace the rail 20 and
clamped thereto by a milled headed binding screw
28 and of a bifurcated downward extension 29
adapted to carry a runner or rubber roller 30
journalled in slots 29' thereof.
- In operation the bar 15 carrying the side lays
19 is mounted on the rails 11 by means of the 100
brackets 16 and clamped thereto by the screws
17' to one side of the feed table 10. The rail 20
adapted to lie at an angle to the side guide 15
as shown in Fig. 1, is then clamped to the rails
11, and upon it are adjusted a number of the 105
rollers 30, the rollers 25 being respectively in con-
tact with the feed rolls at each end of the table
10. The rollers 30 are positioned to bear on the
sheet above selected feed rolls 12 being preferably
set slightly to the rear of the center of each roll 110
in relation to the direction of travel. In this
manner any forward dip in the sheet or tend-
ency to cling to the rolls 12 is obviated whilst by
reason of the rollers 25 and 30 being journalled
in the slots 29' the only pressure exerted upon 115
the sheet is the actual weight of each roller.
- As each sheet is fed forward by the rolls 12 the
line of rollers 30 carried by the inclined bar 20
and set to converge with the side lay 15 at a point
ahead of the travel of the sheet tends to gently 120
force the sheet against the side lay and to main-
tain it square to the direction of travel until it
passes between the fold rolls B. A further series
of guide rollers (not shown) carried in clamps
similar to the clamps 26 may be attached to the 125
rail 11 adjacent to the fold rolls B and set par-
allel to the feed rolls 12. These will serve to con-
trol the forward edge of the conveyed sheet and
subsequently the whole surface thereof to prevent
any tendency to buckle immediately before it is 130
gripped by the fold rolls B.
- It will be observed that the arrangement de-
scribed enables the bar 15 to be readily moved
to any position transversely of the feed rolls 12
by loosening the screws 17' which clamp the 135
brackets 16 to the rails 11, and sliding the whole
side lay to the required position, first having re-
moved the bar 20 with all the roller guides car-
ried thereby. The double sided flange 19 forms
the requisite top guard or retainer for the sheets 140
on either side of the feed table 10. By means of
the brackets 21 and clamping screws 23 the bar
20 carrying the runner guides can then be fitted
in the correct position relative to the side lay 145
15, thus enabling either side or any part of the
feed table to be used for accurate registration of
the sheets. When the side guide is used for feed-
ing sheets with their guide edges to the right, the
bar 20 is, of course, positioned to the left of the 150

side guide at an angle reverse to that of the bar in Fig. 2.

A modified side guide arrangement is shown in Figs. 9, 10 and 11. In this fitting the runner bar and side guide are formed as a unit, comprising a single plate 44 which is provided with a lip 46 in a well known manner. The opposite side of the plate rests upon a block 54 which extends the length of the plate 44 and is seated upon the table frame 41 thus forming an abutment or lay for the left hand edge of the sheet being conveyed toward the fold rolls. Bolted to the block 54 are two or more brackets 55 which are in turn bolted to the side of the frame 41 and so rigidly hold the block 54 in position. A series of elliptical slots 56 are provided in the plate 44 and over each of these slots are positioned ball guide plates 57 pivotally held by milled headed screws 58 which, passing through both the plate 57 and the plate 44, screw into holes 54' drilled into the block 54 and suitably tapped to receive them. A shoulder 59 provided on each screw 58 serves to clamp the guide plates 57 and plate 44 in the required position. Each guide plate is further provided with a hole 60 in which is placed a steel ball 53 which, passing through its respective slot 56 in the plate 44, rests upon the particular feed roll 42 over which it is set.

By this arrangement the position of the balls relative to the feed rolls can be readily and finely adjusted by slackening each screw 58 and swinging the guide plates 57 about their respective pivots, thus traversing the balls 53 in the slots 56 to the required position.

In Figs. 12 and 13 illustrating a method of fitting a ball guide attachment to an existing side lay plate a plate 61 is provided shaped with an upturned lip 62 and a further bent up portion 63 at one end forming a mouth to receive the sheet at the commencement of its travel along the feed table. The plate 61 is also provided with holes 61a for balls 53 as previously described. Steel blocks 64 are fixed on the upper surface of the plate 62 by welding or other methods. A slot 65 is cut in each block 64 at a corresponding angle to that of the lip 70 forming part of the original lay plate 69 and a hole is drilled and tapped through the top face of each block to receive a milled headed screw 66. To attach the ball guide to the original lay plate, the blocks 64 are slipped into position upon the lip 70 and the screws 66 adjusted to hold the plate immovable. The steel balls 53 are then dropped into position and function as previously described.

A further modified fitting is shown in Figs. 14 and 15. The lay plate 44 is shaped and attached to the feed table by the screw fitting 45, 48, 31 in a well known manner. In this form, however, the brackets 45 carry extension pieces 72 which may be adjustable thereon and terminate in jaws 73 each surmounted by a boss 74 in which is tapped a hole to carry a binding screw 75. A circular rod 76 passes through the jaws 73 and is held therein by means of the clamping screws 75. Carried upon the rod 76 are a series of holders or ball smoother guides, one only of which is shown. Each consists of a member 77 cut away to an angle at its lower end to form a mouth 79 and constructed to slidably fit upon the rod 76 being clamped in position thereon by means of the binding screw 78. Extending at right angles from the member 77 is a further portion 77a which terminates in an upwardly inclined lip 79a and is provided with a walled recess 52 which serves

to retain and guide a steel ball 53 as previously described.

In operation each ball smoother guide is positioned on the rod 76 so that the ball 53 carried therein rests upon a feed roll 42 slightly to the rear of the axis thereof whilst the underface of the extension piece 77a is held slightly above the surface of the feed table. The mouth 79 of the extension 77a receives the edge of each sheet as it is conveyed forward and the steel balls 53 guide and control the sheet as previously described whilst the extension piece 77a serves to hold down the sheet passing beneath it thus obviating any tendency the sheet may have to buckle prior to it being seized by the fold rolls.

Referring now to Figs. 16 to 19 inclusive, I have illustrated in these figures the use of a bar 20a mounted upon brackets 21a which are slideable upon the rails 11 and may be clamped in various positions of adjustment thereupon by set screws 23a in a manner similar to that shown in Figs. 1, 2, 5 and 6. This bar is illustrated in connection with a feed table comprising endless tapes 80 running over rollers 81 and 82, one of which may be positively driven by any suitable means, as for instance by a gear 95, connected by suitable gears with a motor (not shown). However, it will be apparent that this bar could be employed to advantage upon a table similar to that of Fig. 2, or upon any other type of table in which the sheet moving elements tend to produce travel of the sheets parallel to the side guide rather than at a slight angle thereto as is common practice.

As in the first described form of the invention I employ as runners, wheels 30a. Each of these wheels has a spindle 83 which is mounted in vertical slots in spaced legs 84 depending from a two-sided bracket having a central wedge-shaped portion 85 and pairs of oppositely extending upper and lower lips 86, either pair of which is adapted to receive the bar 20a and to slide thereupon. The bracket may be secured in any desired position along the length of the bar by threading down the corresponding set screw 87. It will be observed by reference particularly to Fig. 19 that the wedge-shaped portion 85 of the bracket causes the latter, when pushed inwardly against the bar 20a to assume an angular position, thereby bringing runner wheel 30a into angular relation with the bar 20a and hence with the direction of feed of the sheets, this angular position of the individual runners having the same effect of drawing the sheets toward the side guide as does the angular position of the bar 20 in Fig. 2. I am enabled by this means however to apply my invention to a feed table in which the feeding elements are relatively narrow tapes.

In Fig. 17 the feed table is set up to handle sheets with their guide edges toward the left. The side guide and the bar 20a may be moved to other positions transversely of the table, as in the case of the first described form. Now, should the operator desire to feed sheets with their guide edges toward the right, thereby enabling him to reverse the direction of the first fold by merely turning the sheets over, the set screws 23 are loosened and the bar 20a is removed, the side guide 15 is slid across the table to the position shown in Fig. 16, the bar 20a put back upon the rails 11 to the left of the side guide, and the runner brackets removed and put back on the opposite side of the bar 20a, as illustrated in Fig. 16. The angle of the runners 30a is thereby re-

versed, and they are thus positioned to direct the sheets toward the side guide as they travel over the table.

In Figs. 11, 13 and 15 a sheet of paper is indicated at P.

While in the foregoing description and in the accompanying drawings I have illustrated more or less in detail certain specific embodiments of the invention, I desire it to be understood that such detail disclosures have been resorted to primarily for the purpose of fully illustrating the invention in accordance with the requirements of the statute, and are not to be construed as amounting to limitations upon the scope of the invention.

Having thus described my invention, I claim:

1. In a feed table, means for imparting feeding movement to the sheets, a side guide having sheet guiding and retaining surfaces on both sides thereof, a pair of spaced rails mounted at their ends upon the table transversely to the direction of movement of the sheets thereupon, and means for adjustably supporting said guide upon said rails, whereby the guide may be moved transversely of the table into various positions of adjustment.

2. In a feed table, means for imparting feeding movement to the sheets thereupon, means for guiding the movement of the sheets along the table with their guide edges toward either the right or the left, and means supported independently of said guide means adapted to be used upon either side of the table selectively for drawing the sheets outwardly toward the guide and holding them in contact therewith.

3. In a feed table, means for imparting feeding movement to the sheets thereupon, means for guiding the movement of the sheets along the table with their guide edges toward either the right or the left, and means supported independently of said guide means comprising runner wheels adapted to be positioned upon either side of the table selectively with the plane of each wheel directed forwardly and outwardly, whereby the sheets are drawn outwardly toward the guide and held in contact therewith.

4. A side guide for use upon sheet feeding tables, comprising a vertically arranged strip having guide surfaces on either side thereof, and angle bars secured to said strip on opposite sides thereof above said guide surfaces, said bars forming sheet retainers.

5. In a feed table, the combination with a series of cylindrical driven sheet supporting and feeding rollers extending across said table, a supporting bar mounted above the rollers, runners adapted to frictionally engage the rollers of the sheets fed thereby, and means on the supporting bar for carrying the runners and adjusting said runners individually with respect to said bar, whereby their points of engagement with their respective rollers may be shifted forwardly or backwardly.

6. In a feed table, the combination with a series of cylindrical driven sheet supporting and feeding rollers extending diagonally across said table, of a supporting bar mounted above the rollers, holders mounted to swing horizontally upon said bar for adjustment relative to the latter and the rollers, and runners loosely mounted in the free ends of said holders adapted to frictionally engage certain of said rollers, whereby the adjustment of each holder adjusts the runner carried thereby with respect to its roller.

7. In a feed table, the combination with a series of cylindrical driven sheet supporting and feed-

ing rollers extending across said table, of a supporting bar mounted above the rollers, said bar having longitudinal slots therethrough, holders mounted to swing horizontally upon said bar for adjustment relative to the latter and the rollers, and balls loosely mounted in the free ends of said holders and extending through said slots for frictional engagement with the rollers, whereby the adjustment of each holder adjusts the ball carried thereby with respect to its roller.

8. In a feed table, means for advancing sheets thereupon, a pair of spaced rails extending transversely of the table from one side to the other thereof, a side guide and a supporting bar mounted upon said rails for independent movement transversely of the table, and a plurality of runner wheels mounted upon said bar with their planes inclined forwardly and outwardly toward said side guide.

9. In combination, a frame, a feed table fixed thereupon, said table comprising means for imparting feeding movement to the sheets, a side guide, means for supporting the side guide at either side of the table, a supporting bar adjustably mounted upon the frame independently of said guide, said bar being adapted to be positioned upon either side of the guide with its forward end converging toward the guide, and means carried by the said bar for drawing the sheets toward said guide in either position of the bar, whereby sheets may be fed with their guide edges toward the left or the right side of the table.

10. In a feed table, means for advancing sheets thereupon, a side guide, a supporting bar extending longitudinally of the table, runner wheels carried thereby adapted to engage sheets traveling over said sheet advancing means to heighten the tractive effort of said means, and mounting means for said supporting bar permitting movement of the bar toward and away from said side guide and permitting a variation in the angle between the bar and the side guide.

11. In a feed table of the type having sheet feeding and supporting rollers extending diagonally thereof, a sheet guide at one side of the table and having a flange overhanging the same, a ball retaining plate having openings therein to hold sheet engaging balls in operative relation with said rollers, and means for detachably securing said plate on said flange and providing for adjustment of the plate and said balls laterally and longitudinally with respect to said table.

12. In a feed table of the type having sheet feeding and supporting rollers extending diagonally thereof, a sheet guide at one side of the table and having a flange overhanging the same, a ball retaining plate having openings therein to hold sheet engaging balls in operative relation with said rollers, said plate being flared upwardly at one end to guide the sheets thereunder, and means for detachably securing the plate on said flange and providing for adjustment of the plate and said balls laterally and longitudinally with respect to said table.

13. In a feed table, a series of cylindrical driven sheet supporting and feeding rollers extending diagonally thereof, a sheet guide adapted to be mounted adjacent one side of the table, means adapted to adjust the sheet guide transversely of the table at right angles to said side thereof, rotatable sheet engaging devices cooperating with the sheet supporting and feeding rollers, and holders for the rotatable sheet en-

gaging devices, said holders being mounted on the sheet guide and adapted for adjustment to shift said rotatable devices and aline them with said rollers when the sheet guide is adjusted as 5 aforesaid.

14. In a feed table, a series of cylindrical driven sheet supporting and feeding rollers extending diagonally thereof, a sheet guide adapted to be mounted adjacent one side of the table, means 10 adapted to adjust the sheet guide transversely of the table at right angles to said side thereof,

a plurality of sheet engaging balls cooperating with the sheet supporting and feeding rollers, a plurality of holders mounted on the sheet guide and having openings through which the balls extend, and means providing for adjustment of the holders longitudinally of the sheet guide when the latter is adjusted transversely of the table as aforesaid, whereby the balls may be maintained in alinement with, and proper position relative to, said diagonally extending rollers. 80 85
